ATTACHMENT FOR INTERCHANGEABLE HANDLES

Robert C. Clark and Arnold E. Hahn,
San Francisco, Calif.

Application July 13, 1931. Serial No. 550,398

1 Claim. (Cl. 306—30)

This invention relates to attachments for interchangeable handles for brooms, brushes and the like, and particularly relates to a type of such attachments whereby the handles of push brooms and the like may have eliminated therefrom the usual thread on the connecting end which attaches to the block of a broom.

While the invention is described herein with relation to push brooms, it is to be understood 10 as adaptable for use with mops, wall cleaning brushes, window cleaning devices and the like.

Heretofore it has been customary to manufacture handles for devices of the kinds above mentioned and provide at the end thereof which is 15 to be connected to the broom or mop, a threaded portion which is adapted to be engaged in a threaded recess in a broom block. These handles are made of both hard and soft wood, and in the case of soft wood, the cutting of the thread 20 reduces transversely the size of the handle so that there is the likelihood of breaking of the threaded shank from the handle, and also likelihood of breakage in the handle from its normal use or from being stepped on by the operator. 25 In the case of hard wood handles, it is difficult to cut the thread, the threaded shank is liable to break at point of connection with the handle, and in both the hard wood and soft wood handles, the threads of the shank chip off due to 30 the fact that they run with the grain of the wood and the threads have no lateral support.

By providing an attachment for connecting handles to broom blocks in which the threaded shank is rigid metal, and a tubular sleeve is 35 provided of resilient material, the thread of the wooden handle may be entirely eliminated and handle members of varying transverse dimensions may be used, and the handles may be made interchangeable, thus accomplishing a saving in 40 the cost of cutting threads on the handle, and also making the handles interchangeable in case of breakage.

Objects of the invention are to provide an attachment for connecting push broom handles to 45 a broom block and wherein the handle may be interchangeable; to provide such an attachment wherein the usual threaded portion of a push broom handle may be eliminated; to provide such an attachment having a resilient portion to engage 50 the handle and a rigid portion to engage the push broom block; to provide such an attachment in an integral structure wherein one portion is resilient and another portion rigid.

With the above mentioned and other objects in 55 view, the invention consists in the novel con-

struction and combination of parts hereinafter described, illustrated in the accompanying drawing and pointed out in the claim hereto appended; it being understood that various changes in the form, proportion, size and minor details 60 of construction within the scope of the claim may be resorted to without departing from the spirit or sacrificing any of the advantages of the invention.

To more clearly comprehend the invention, 65 reference is directed to the accompanying drawing, wherein—

Fig. 1 is an end view of push broom with handle 70 therein, showing position of handle attachment device.

Fig. 2 is a longitudinal side view of device.

Fig. 3 is a plan view.

Fig. 4 is an end view in direction of arrow 4—4 of Fig. 2.

Fig. 5 is a transverse vertical section on line 75 5—5 of Fig. 2.

Fig. 6 is a plan view showing a modified fastening means.

Fig. 7 is a longitudinal side view, showing 80 a modified fastening means.

Referring to the drawing, wherein like characters of reference designate corresponding parts, 10 represents generally a push broom having a broom block 11 provided with bristles 12 and having connected thereto an elongated handle 13. 35 An elongated tubular sleeve member generally indicated 14 is provided, which is adapted slidably to receive through an open end 14^a one end portion of the broom handle 13, the opposite end of the sleeve being flanged radially inwardly upon 90 itself, providing a shoulder 14^b which has an elongated extension or shank 16 which is preferably tubular and is provided with a helical thread 16^a. It is preferred that the sleeve and threaded shank 95 be formed of an integral sheet of spring metal such as sheet steel of about 20 gauge, which is readily obtainable in the commercial market.

The main body portion 14 of the tubular sleeve is preferably arcuate in lateral transverse cross section, providing substantially parallelly spaced 100 edges 17 and 18, each of said edges being provided with means whereby the transverse cross sectional diameter of the sleeve portion 14 may be contracted, said means as exemplified consisting of outwardly turned lugs or ears 20 and 21, which, 105 in Fig. 3, are shown as being two on each of the edges 17—18, and in Fig. 7 as one elongated ear on each edge.

The ears 20—21 have openings 20^a and 21^a through which are received headed bolts 22, 23, 110

which are threaded as at 24, and are adapted to draw the parallel edges 17, 18 toward each other by suitable threaded engagement at the end opposite the head. In Fig. 3 this threaded engagement is accomplished by means of internally threaded burrs 25 formed inwardly from the metal of the ears, whereas in Fig. 6 the bolts are engaged by an internally threaded nut 26. The material having a degree of resiliency, as above stated, it is apparent that the sleeve portion 14 will have a degree of resiliency in its arcuate form so that when a broom handle is placed therein and the bolts tightened, the handle will be securely held therein, and so that the handle 15 may be removed by loosening the bolts.

Because of the shoulder 14^b being flanged radially inwardly from the wall of sleeve 14, it is obvious that there will be substantially no resiliency at the flanged end but that the resiliency 20 will increase by degrees in the direction of the open end 14^a. The corrugations formed by the threads 16^a of shank 16 will reinforce the walls

of the shank to an extent that radial resiliency of the shank will be completely negated, and a tight abutment will be formed by the parallel abutting opposing edges 27, 28 of the shank wall.

Having thus described our invention, what we claim and desire to secure by Letters Patent is:—

A device of the character described comprising an elongated tubular longitudinally split sleeve open at one end and flanged radially inwardly at the opposite end providing a circumferential shoulder, a rigid externally threaded hollow cylindrical shank extended from said flanged shoulder portion and of lesser lateral transverse diameter than the tubular sleeve, and said sleeve including means whereby the sleeve may be releasably clamped about an implement handle, said sleeve and threaded end portion being of substantially uniform thickness of material whereby said device may be formed from sheet metal.
